UNITED STATES PATENT OFFICE.

JULIUS N. LISK AND NELSON J. LISK, OF TROY, OHIO.

GRINDER.

No. 856,167.

Specification of Letters Patent.

Patented June 4, 1907.

Application filed July 7, 1906. Serial No. 325,120.

To all whom it may concern:

Be it known that we, JULIUS N. LISK and NELSON J. LISK, citizens of the United States, residing at Troy, in the county of Miami and State of Ohio, have invented 5 certain new and useful Improvements in Grinders; and we do hereby declare the following to be a full, clear, and exact description of the invention, such as will enable 10 others skilled in the art to which it appertains to make and use the same.

Our invention relates to new and useful improvements in grinders and more particularly to that class adapted to be used in 15 grinding coffee, spices or the like and our object is to provide means for purifying the articles after they are ground by removing the dust, husks and finer particles of the articles.

20 Other objects and advantages will be hereinafter referred to and more particularly pointed out in the claims.

In the accompanying drawings which are made a part of this application, Figure 1 is 25 an elevation, partly in section, showing an electrically operated mill with our improved device attached thereto. Fig. 2 is a similar view with our improved attachment applied to the opposite side of the mill. Fig. 3 is an 30 elevation of a manually operated grinder with our improved attachment applied thereto. Fig. 4 is a plan view of a slightly modified form of construction, and Fig. 5 is a detail perspective view partly in section of 35 a valve and parts coöperating therewith.

Referring to the drawings in which similar reference numerals designate corresponding parts throughout the several views, 1 indicates a grinding mill of that class adapted 40 to be used in grinding coffee, spices or the like, and 2 indicates a motor which is preferably an electric motor, by which means the grinder is operated.

A shaft 3 is disposed through the motor 45 and extends beyond each end thereof, the grinding mill 1 being operatively connected to one end of said shaft while to the opposite end thereof is secured a suction fan 4 around which is disposed a suitable housing 5 having 50 a discharge chute 6 at a point on its periphery, the housing being supported on a suitable base member 7.

The mill 1 is provided at its upper end with a hopper 8 in which articles to be ground are 55 deposited after which they pass through the burs of the mill (not shown) and are direct-

ed through a tubular member 9 below the burs and into a drawer like receptacle 10 at the extreme lower end of the mill. A suction pipe 11 is secured at one end to the tubular member 9 immediately over the drawer 10, the opposite end thereof being disposed through one side of the housing 5 so that when the ground material is deposited into the drawer 10, the dust arising therefrom 60 will be drawn through the pipe 11 by the suction fan 4 and discharged through the chute 6, said chute being directed into any suitable receptacle for receiving the dust.

The force of the suction pipe through the 70 pipe 11 is regulated by means of a valve 12, said valve being pivotally secured in the pipe 11 by means of a stem 13, to the upper end of which is pivotally secured a latch 14, said latch being adapted to engage with notches 75 in a keeper 15 mounted upon the pipe 11 in juxtaposition to the stem 13. By this construction it will be seen that the valve 12 may be adjustably secured in any position by moving the latch 14 to the right or left and 80 securing the same in one of the notches in the keeper.

In Fig. 2 of the drawings, the shaft 3 is disposed through the mill 1 and the suction fan 4 is disposed on the opposite side of the 85 grinding mill to that shown in Fig. 1.

In Fig. 3 we have shown a mill adapted to be manually operated with our improved suction fan secured thereto, the fan being operated from the power wheel 15', a belt 17 90 extending from the power wheel to a pulley 18 on the fan shaft 19 while in Fig. 4 we have shown the suction fan disposed to one side of the mill and operated by a driving belt or the like 16 which is connected to any source 95 of motive power and independent of the power driving the mill.

By this construction it will be seen that we have provided a cheap and efficient means for collecting and removing the dust and 100 husks and finer particles of foreign substances from the ground material, and thereby purifying the coffee and the like so that the same will be less injurious to health as it is a well known fact that the dust from the 105 ground berry renders the coffee unpalatable and very injurious to health.

What we claim is:

The herein described attachment for grinding mills comprising the combination 110 with a mill having grinding mechanism therein, a shaft extending through said mill and

grinding mechanism, a tubular member below said grinding mechanism, a receptacle at the lower end of said tubular member; of a fan secured to one end of said shaft, a housing 5 for said fan, a discharge chute for said housing, a pipe, one end of which is directed into engagement with said tubular member and below the grinding mechanism while the opposite end thereof enters said housing at its 10 axial center, a rotatable valve in said pipe, means to hold said valve in its adjusted po-

sition and additional means to rotate said shaft.

In testimony whereof we have signed our names to this specification in the presence of 15 two subscribing witnesses.

JULIUS N. LISK.
NELSON J. LISK.
